PRECAST OUTDOOR FIREPLACE

Richard E. Barber, Elmira, N.Y.

Application December 27, 1957, Serial No. 49,048

Term of patent 14 years

(Cl. D81—7)

FIG.1.

FIG.2.

Figure 1 is a perspective view of the precast outdoor fireplace; and

Figure 2 is a top plan view of the precast outdoor fireplace.

The back of the fireplace is essentially the same in appearance as the front, aside from the inset rectangular slab across the top rear illustrated in Figure 1. The side of the fireplace, not shown in Figure 1, is substantially the same as the side shown, with the omission of the clean-out hole.

I claim:

The ornamental design for a precast outdoor fireplace, substantially as shown and described.
